FASTENING INSERTING MACHINE

Harold Lane and William Arthur Barton,
Leicester, England, assignors to United Shoe
Machinery Corporation, Flemington, N. J., a
corporation of New Jersey

Original application June 3, 1941, Serial No.
396,438. Divided and this application July 18,
1942, Serial No. 451,446. In Great Britain June
7, 1940

6 Claims. (Cl. 1—20)

This invention relates to fastening-inserting machines and is herein illustrated as applied to a machine of the type disclosed in Letters Patent of the United States No. 2,318,083, granted on May 4, 1943, upon an application of Lane and Barton, of which this application is a division, said machine having means for tensioning a shoe upper over a last and fastening-inserting means movable relatively to the last into position to fasten the upper to a sole. It will be understood, however, that this invention is not limited to machines of that particular type nor, in certain respects, to machines for fastening shoe uppers.

Machines of the illustrated type are each provided with fastening-inserting mechanism which comprises a guide for the fastenings, the guide cooperating with fastening-driving means, and a deflector at the outlet end of the guide for engaging the fastening before it enters the work and for bending it progressively in the driving operation to cause it to follow a curved path in the work, and in accordance with a feature of the invention novel means is provided for adjusting the initial position of the guide relatively to the deflector to vary the degree of curvature of the fastening. In the illustrated construction, the fastening-inserting mechanism is particularly adapted to insert staples and is constructed and arranged to effect relative movement of the driver and the deflector in a direction at an angle to the line of drive near the end of each operative movement of the driver to cause the driver to complete the driving of the staple fully into the work. Since it is desired in the illustrated machine to maintain the staple deflector in a permanently fixed position relatively to its supporting slide, means is provided for initially adjusting the staple guide and the direction or angle at which the driver moves relatively to the deflector to determine the degree of curvature to be imparted to the staple legs by the deflector.

The above and other novel features of the invention, including novel details of construction and combinations of parts, will now be more particularly described by reference to the accompanying drawing and will be pointed out in the claims.

In the drawing,

Fig. 1 is a view in left-hand side elevation of a portion of the head of a machine in which the invention is embodied, showing the parts in the positions they assume substantially at the end of the staple-driving operation;

Fig. 2 is a section on the line II—II in Fig. 1;

Fig. 3 is a section on the line III—III in Fig. 2;

Fig. 4 is a section on the line IV—IV in Fig. 1; and

Fig. 5 is a detail view of a portion of the staple-driving mechanism of the machine and showing the means for varying the direction of movement of the driver.

The invention is illustrated as embodied in a machine of the type disclosed in the above-mentioned Letters Patent and, accordingly, only such features of the general organization as it is necessary to refer to for an understanding of the invention will be described herein in detail. It will be understood that a machine of this type is provided with a side gage 10 (Fig. 1), a sole rest (not shown) serving to position the shoe, shoe-upper-tensioning mechanism, and fastening-inserting means such as a staple-driving mechanism 13 cooperating with a deflector 14 carried on the forward end of a slide 12, the slide 12 being mounted in the machine head for forward movement toward the operator in a downwardly inclined path, the slide also carrying the staple-driving mechanism. The upper-tensioning mechanism is arranged progressively to tension unlasted portions of the upper over the last and insole along the edge of the bottom of the shoe, held in the operator's hands. In time relation to each pulling of the upper a staple is driven by the staple-driving mechanism to fasten the tensioned marginal portion of the upper to the insole. As the staple is driven, its legs are engaged by the deflector 14, the deflector acting to curve successive portions of the legs before they enter the work to cause the legs to follow curved paths and to become effectively anchored in the insole. Moreover, in time relation to each upper pulling operation, the slide 12 is moved forwardly to carry the lower end of the staple-driving mechanism, usually referred to as a staple-guiding nozzle 15 (Fig. 5), and other parts associated therewith, inwardly over the shoe bottom to lay the marginal portion of the upper over the insole, whereupon the staple is driven and thereafter the slide 12 is retracted to its starting position.

45 The staple-driving mechanism 13 (Fig. 1) is provided with a staple driver 34 (Fig. 5).

The staple-driving mechanism 13 and its actuating means are similar to those disclosed in Letters Patent of the United States No. 2,242,423, granted May 20, 1941, upon an application filed in the names of Elliott and Mawbey, and accordingly, only so much of them will be described here as is necessary for an understanding of this invention. As disclosed in that patent, the staple-guiding nozzle 15 is mounted to tip about the

axis of a horizontal pin 108 (Fig. 5) projecting from a forward extension 110 on the slide 12. The driver-operating means, to be described, is so constructed that at a predetermined time in the operation of the driver, preferably at the time when the crossbar of the staple is engaged by the deflector 14, the staple-guiding nozzle 15 is tipped about the axis of the pin 108 to move the staple-engaging end of the driver 34 heightwise of the deflector 14 toward the work. The pin 108 is so located that, as the driver 34 is thus tipped with the guiding nozzle 15 during the remaining portion of its operative stroke, its staple-engaging end moves in a path approaching parallelism with the deflecting face of the deflector. The pin 108 is located just above a guideway 112 in the nozzle 15 and the driver 34 normally extends into the guideway 112.

In the illustrated construction, the staple deflector 14 is rigidly mounted on the supporting slide 12 opposite the outlet end of the staple-guiding nozzle 15 and, hence, for the purpose of adjusting the degree of curvature imparted to the staple legs during the driving of a staple, it is desired to adjust initially the distance between the outlet end of the nozzle 15 and the deflecting face of the deflector, as well as the angularity of the driver's approach to the deflector, prior to the driving of a staple to determine the curvature of the legs of the staple to be driven. As in the construction disclosed in the above-mentioned Elliott and Mawbey patent, the driver 34 is secured to a slide 114 (Fig. 5) which is reciprocated a uniform distance in guideways formed in the nozzle, the slide 114 being pivotally connected at 116 to a link 118 the forward or upper end of which is pivotally secured at 119 to the upwardly extending arm 120 of a bell-crank lever which is oscillated by cam-operated mechanism, similar to the corresponding mechanism described in the above-mentioned patent, to impart staple-driving and tipping movements to the driver 34. For the same purpose as stated in the said patent, the link 118 is pivotally secured by a pin 126 substantially midway between its ends to an arm 122 which is longer than the arm 120 and is mounted for swinging movement about a fixed fulcrum stud 124.

In order to permit an initial adjustment of the staple-guiding nozzle 15 relatively to the staple-deflecting face of the deflector 14 prior to the driving of a staple, the hub of the arm 120 is rotatably mounted on an eccentric sleeve 128 (Figs. 4 and 5), the sleeve itself being rotatably mounted on a stud 130 supported in a bracket 132 (Fig. 1) which, as more fully disclosed in the above-mentioned patent, is adjustably secured to the slide 12. The eccentric sleeve 128 has secured on its right-hand end (Fig. 4) a hand lever 134 by which the sleeve may be rotated. The hand lever has mounted in it a spring-pressed plunger 136 which is arranged to engage either of two notches 138 (Fig. 5), one of which is formed in a segment 140 secured to the right-hand end of the stud 130 (Fig. 4) and the other of which is formed on a segment 142 which is adjustable about the stud 130 and is located between the hand lever 134 and the segment 140. The segment 140 has formed in it an arcuate slot 144 through which a screw 146 passes. The screw is threaded into the segment 142 and serves to clamp the two segments 140 and 142 together. If the screw 146 is slackened, the segment 142 may be adjusted about the axis of the stud 130 to

vary the distance between the two notches 138 and, accordingly, the extent of movement of the hand lever 134.

The axis of the eccentric sleeve 128 is offset from the axis of the stud 130 only a relatively small amount and in the position of the parts shown in Fig. 5 this axis is located at the rearward or left-hand side of the axis of the stud. The eccentric sleeve 128 is so arranged that in either position of adjustment of the hand lever 134 the driver 34 completes its staple-driving stroke in substantially the same position relatively to the deflector 14, or in other words the final position of the staple-engaging end of the actuated driver 34 relatively to the staple-deflecting face of the deflector 14 remains unaltered.

When, however, the staple driver 34 is in its retracted position, adjustment of the eccentric sleeve 128 from one position to the other raises or lowers the pin 119 pivotally connecting the link 118 with the arm 120, thus raising or lowering the lower end of the staple-guiding nozzle 15 relatively to the deflecting face of the deflector 14. Accordingly, the distance between the lower end of the staple-guiding nozzle and the deflecting face of the deflector 14 is either decreased or increased and at the same time the angle of movement of the driver relatively to the deflector is changed. This results in a corresponding change in the degree of curvature imparted to the legs of the staple to be driven.

In the machine disclosed in Letters Patent of the United States No. 1,815,295, granted on July 21, 1931, upon an application of George Goddu, the staple wire is fed from a reel of wire and the winding of the wire on the reel causes the wire, when it is drawn from the reel, to have a tendency to curve in one direction and thus make accurate measuring of a length of wire difficult. To overcome this obstacle, the following mechanism is provided. The present machine has, similar to the machine disclosed in the Goddu patent, a wire-guiding nozzle 148 (Fig. 2) which, together with a so-called inside staple former 150, is mounted on the slide 12 and, therefore, both members 148 and 150 participate in the forward and rearward movements of the slide. The wire-guiding nozzle 148 serves to present an extent of wire, fed through the nozzle by mechanism disclosed in the Goddu patent, to a substantially U-shaped outside former 152 secured to a block 156, together with a wire-severing knife 154, the block itself being secured to the machine frame. The wire-feeding operation of the nozzle 148, to present an extent of wire to the outside former 152, is terminated by an adjustable stop. For the purpose of the present invention the stop is in the form of a spring-pressed plunger 158 (Fig. 3) slidably mounted in a bore provided in the block 156, the longitudinal axis of the plunger being in alignment with the outlet end of the nozzle 148 when the end of the wire is fed through the nozzle (Fig. 3). One end of the plunger 158 is held by a coil spring 160 located in the bore in the block 156 against the outside former 152 provided with wire-guiding slots through which the wire is fed. In the center of the end face of the plunger 158 adjacent to the outside former 152 is formed a small recess into which the end of the wire is fed. The inner end of the spring 160 is mounted on the reduced portion 164 of a screw 162 threaded into the bore of the block 156, the portion 164 acting as an adjustable stop for the plunger 158 when the latter is moved inwardly as a result of the feeding of the wire. The spring

160 is relatively light and, when the wire is being fed through the slots of the outside former 152, the wire end enters the recess in the plunger 158 and, as the wire continues to be fed, the plunger 158 is pushed back until it engages the stop 154, the latter, therefore, determining the length of wire fed in. As the plunger 158 is moved back or inwardly by the wire against the pressure of the light spring 160, the engagement of the wire end with the recess in the plunger 158 causes the wire to be moved in a straight path, with the result that the correct length of wire is measured.

The staple wire-feeding mechanism above described but not claimed herein has been made the subject-matter of a divisional application Serial No. 498,544, filed August 13, 1943, in our names.

Having thus described our invention, what we claim as new and desire to secure by Letters Patent of the United States is:

1. In a fastening-inserting machine, means for driving a fastening, a guide for the fastening cooperating with said driving means, a deflector at the outlet end of the guide for engaging the fastening before it enters the work and for bending it progressively during the driving operation to cause it to follow a curved path in the work, and means for adjusting the initial position of said guide relatively to the deflector to vary the degree of curvature of the fastening.

2. In a fastening-inserting machine, the combination with shoe-positioning means of means for fastening the upper of a shoe to a sole, the fastening means comprising a driver movable in a direction at an angle to the bottom face of the sole to drive the fastening through the upper and into the sole, a nozzle for guiding the fastening and the driver, a deflector for engaging the fastening before it enters the work and for bending it progressively during the driving operation to cause it to follow a curved path in the work, and means acting on the nozzle for varying the angle of drive of the driver relatively to the deflector to vary the curvature of the fastening.

3. In a fastening-inserting machine, the combination with a driver for driving fastenings and a deflector arranged to act on different portions of each fastening successively before the different respective portions enter the work to bend the fastening progressively as it is driven, of means for effecting relative movement of the driver and the deflector in a direction at an angle to the line of drive near the end of each operative movement of the driver to cause the driver to complete the driving of the fastening fully into the work, and means for initially adjusting the direction of movement of the driver relatively to the deflector to determine the degree of curvature to be imparted to the fastening by the deflector.

4. In a fastening-inserting machine, the combination with a driver for driving fastenings and a deflector arranged to act on different portions of each fastening successively before the different respective portions enter the work to bend the fastening progressively as it is driven, of means

5 for tipping the driver substantially at the end of its driving stroke toward the work to cause the driver to complete the driving of the fastening fully into the work, and an eccentric member included in the driver-tipping means for initially adjusting the direction of movement of the driver relatively to the deflector to determine the degree of curvature to be imparted to the fastening by the deflector.

10 5. In a fastening-inserting machine, the combination with a driver for driving fastenings and a deflector arranged to act on different portions of each fastening successively before the different respective portions enter the work to bend the fastening progressively as it is driven, of means 15 for effecting relative movement of the driver and the deflector in a direction at an angle to the line of drive near the end of each operative movement of the driver to cause the driver to complete the driving of the fastening fully into the work, and means for initially adjusting the direction of movement of the driver relatively to the deflector to determine the degree of curvature to be imparted to the fastening by the deflector, the adjusting means being arranged to cause the driver 20 always to conclude its driving stroke in the same position relatively to the deflector regardless of the initial adjustment of the direction of movement of the driver.

30 6. In a fastening-inserting machine, the combination with a staple-guiding nozzle having a guideway for a staple inclined at an angle to the face of the work into which the staple is to be driven, the nozzle being mounted for tipping 35 movement about an axis extending crosswise to said guideway, and a deflector opposite to the nozzle for engaging the legs of the staple to curve different portions of the leg successively in the driving operation before the different respective 40 portions enter the work to cause them to follow curved paths in the work, of a driver for driving a staple through said nozzle in the direction of said guideway, means for operating the driver and for tipping the nozzle about its axis in a direction 45 to cause the staple-engaging end of the driver to move relatively to the deflector toward the work to force the staple fully into the work, said operating means comprising a slide movable in a guideway in said nozzle, a lever for operating said 50 slide, a link connecting the slide and said lever, a pair of arms of unequal lengths pivotally connected to said link and so arranged as to cause the movement of the lever to be transmitted to the slide, first in a substantially straight line path 55 parallel to the driver and then in a path at an angle to the driver to tip the nozzle substantially at the end of the operative movement of the driver, and an eccentric bearing for one of said arms adjustable to tip the nozzle prior to the operative movement of the driver so as to vary the position of the nozzle relatively to the deflector to determine the degree of curvature to be imparted to the fastening by the deflector.

HAROLD LANE.

WILLIAM ARTHUR BARTON.
